EMERGENCY FUEL CONTROL

Wilfred S. Bobier, Jr., Grosse Pointe, Mich., assignor to George M. Holley and Earl Holley

Application April 20, 1948, Serial No. 22,037

9 Claims. (Cl. 158—36.3)

1

This invention relates to the supply of fuel to a power plant of the type in which fuel flow controls speed, for example, a gas turbine.

The object of this invention is to transfer from the normal fuel supply system to an emergency fuel supply system whenever the normal fuel supply system fails to maintain the selected fuel supply and speed.

Fig. 1 shows the preferred form of my invention.

Fig. 2 shows a detail taken on plane 2—2 of Fig. 1.

In Fig. 1 fuel enters the passage 58 from which it is delivered to the turbine through two fuel pumps, the primary pump 60 and the emergency pump 62. The primary pump 60 discharges the primary fuel through a passage 78, into the primary governor 108, past the check valve 110, along the passage 111 to the outlet 114 of the gas turbine, not shown.

When the check valve 110 is closed and the emergency check valve 112 is open fuel flows from the passage 58, through the emergency pump 62, along the passage 76, through the passage 14 to the emergency governor 104 and check valve 112. The control levers 102 and 106 and a speed setting cam 90 are all linked together by linkage 103—105.

In the position shown the selector valve 70 is shown in the position in which the emergency fuel pump 62 is inactive. The fuel then flows from the emergency pump 62, through the passage 76 into the chamber 64 and back through the passage 63 to the passage 58.

During operation a rotating casing 43 is rotated by the shaft 41 which is driven by a gas turbine. This casing 43 carries a centrifugal weight 26 which is supported by a spring 28 and reciprocates in a cylinder 27. This casing 43 rotates in a chamber 12 which communicates through a passage 10, a passage 79, to the outlet 78 of the primary pump 60. This fuel in the chamber 12 is thus at the highest pressure developed by the primary pump 60.

The pressure in the pipe 109, connecting the primary governor 108 with the primary check valve 110 is at a lower pressure than the fuel in the chamber 12. A passage 14 connects the passage 109 with the passage 19 in the center of the shaft 41. The passage 19 is connected to the port 18, which port is controlled by the valve 22. Valve 22 is provided with an opening in its center 23. When the spring 28 pushes the weight 26 up it raises the valve 22 and admits high pressure fuel through the passage 24 and port 25

2

through the passage 23 to the inner end of the cylinder 27, to the passage 47 and ports 42 and 48. Passage 23 communicates through the restriction 29 through passage 32, to the chamber 33 which is to the right of a diaphragm 34. Chamber 30, located to the left of the diaphragm 34, is subjected to the pressure in the chamber 12.

The passages 14 and 19 also communicate with the cylindrical chamber 16, above and below the perforated piston valve 44, which is normally in the position shown, that is to say, in the position in which the port 48 is closed whenever the turbine is running. When the turbine is not running and when it is running at extremely low speeds the spring 46 pushes the element 44 down, causes the port 48 to open and thus the pressure difference between the chamber 16, the port 48 and chamber 33 becomes zero.

A similar perforated piston valve 38 is pushed radially in towards the center by the spring 40 so as to close the port 42 at all times except at extremely high speeds. Both sides of the element 38 communicate at all times with the high pressure fluid in the chamber 12. Normally the element 38 is in the position shown so that normally the port 42 is closed. Normally the element 44 is in the position shown closing the port 48. Both elements 44 and 38 are perforated so that the fluid pressure is the same on both sides of the two valves thus both valves respond only to centrifugal and spring forces.

A flywheel 57 is connected to the rotating casing 43 through a spring 59. Flywheel 57 carries the radial port 52 which communicates with the passage 32 in the center of the flywheel 57.

During acceleration, the flywheel 57 tends to lag behind the casing 43. This brings the port 52 in line with the restriction 50 in the casing 43, thus forming a direct passage from the passage 19 through the restriction 50, through the radial passage 52 to the axial passage 32. Thus a bypass is opened around the valve 22 and restriction 29 but this bypass only remains open during acceleration and closes the moment that steady speed is reached.

A cam 90 engages with a perforated piston 91 which compresses a spring 92 which engages with a piston 88; the piston 88 engages with a spring 96, spring 96 engages a valve 54, and valve 54 engages with the diaphragm 34. The chamber 93, to the left of the piston 88, communicates through a restriction 95 with a passage 97 and with the chamber 33 to the right of the diaphragm 34. Valve 54 is located between the low pressure fluid passage 56 and passage 55.

A manually operated lever 115 controls a valve 116 in the passage 55 connecting the valve 54 with a chamber 68, to the left of selector valve 70. A valve 82, normally closed by spring 84, is controlled by an electromagnetic element 77 so that the valve 82 can be opened when desired.

A spring 69 tends to move the valve 70 against the pressure in the chamber 68. A spring loaded non-return valve 80 connects the passage 76 with the chamber 68. A spring loaded non-return valve 120 connects the chamber 12 with the chamber 68. Valve 70 has two valve seats 67 and 71 and is shown seating on valve seat 67 which is the position for normal operation.

Operation

The moment the emergency pump 62 and the primary pump 60 start to work the valve 54 moves to the right as pressure is delivered to chamber 30, on the left hand side of the diaphragm 34. Chamber 33 communicates through port 50 with the low pressure passages 14 and 19. Check valve 120 admits pressure from primary pump 60 to passages 78-79-10 to chamber 12 and so to chamber 68 on the left hand side of selector valve 70 which compresses spring 69 and closes valve seat 67 and at the same time opens a path past valve seat 71.

During the actual start when the turbine is rotating at very slow speeds the spring 46 holds the valve 44 down so that port 48 remains open. Port 48 being open chamber 33 is in direct communication with the passage 14, that is, with the pressure downstream of the primary governor 108. Valve 54 is thus held in its inoperative position by the pressure on the upstream side of the primary governor 108.

Opening valve seat 71 permits the emergency pump 62 to discharge fuel freely through passage 76 past the valve seat 71, through passage 58 back to the fuel entrances to pumps 60 and 62. Valve seat 71 remains open at all speeds where the cam 90 does not impose sufficient load on springs 92 and 94 to open valve 54. During acceleration the piston 88 temporarily delays the application of pressure on the diaphragm 34 by means of the restriction 95 and chamber 93. Port 52 and two restrictions 50 and 29 decrease the pressure on the diaphragm 34 temporarily. Hence, the cam 90 can be rotated anti-clockwise to increase the speed without putting the mechanism into the emergency position, unless there is a failure to respond to the increase in speed called for within a reasonable interval of time.

If an emergency occurs so that the primary governor 108 fails to supply the fuel to produce the speed called for by the position of cam 90 and of lever 106 then the weight 26 is pushed radially in by spring 28 and high pressure is transmitted from primary pump 60 through pipe 78, through passage 79, through passage 10, through chamber 12, through passages 23 and 24, past port 25, then through passage 32 to the chamber 33, on the right hand side of diaphragm 34. Valve 54 then travels to the left and admits low pressure from pipe 58 through pipe 56 to passage 55. Valve 54 remains there as low pressure to the left of valve 70, in chamber 68, moves valve 70, closes seat 71 and opens seat 67. This drops the pressure in chambers 12 and 30 to that of the pipe 58. As long as valve 54 is open chamber 68 remains at a low pressure.

Testing operation

If valve 82 is opened to make sure that the emergency system if called upon will work and it

is desired to get back into the primary system then valve 82 is closed by opening the switch controlling the electromagnetic element 77. This puts the system into primary position as a rule.

To make sure of getting back into primary system, lever 115 is momentarily moved so as to momentarily close passage 55 (equal to closing valve 54). Pressure is thereupon admitted to chamber 68 past check valve 120, this moves valve 70 to the right.

If it is desired to lock out the emergency governor system then lever 115 is left in its closed position.

If it is desired to lock out the primary system the valve 82 is left in its open position so that valves 54 and 116 are then both inoperative.

Speed sensing device

The speed sensing device has been described in my copending application Serial No. 783,071, filed October 30, 1947.

Briefly, the pressure in the inner end of the cylinder 27 equals the pressure in the chamber 12 plus the force exerted by the spring 28, minus the centrifugal force of the weighted piston 26.

Hence, the difference in pressure across the diaphragm 34 is a function of the speed. The motion of the cam 90 regulates the speed, below which the valve 54 moves to the left, and so brings the emergency system into action in place of the primary governor and primary pump.

What I claim is:

1. An emergency fluid fuel control system for a power plant of the type in which fuel flow controls speed, having a source of fuel, a primary fuel inlet passage to said plant, a primary fuel pump located in said passage, a primary governor located in said passage intermediate between the pump and power plant and controlling the flow of fuel from said primary pump to said power plant, an escape passage located intermediate between the pump and the governor, an emergency fuel inlet passage to said plant, an emergency fuel pump located in said passage, an emergency governor located in said passage intermediate between the pump and the power plant and controlling the flow of fuel from said emergency pump to said power plant, an escape passage located intermediate between the pump and the governor, a control valve located in each escape passage, interconnecting means for the two valves so that if one escape passage is opened the other is closed, automatic means including a third fuel governor having centrifugal means responsive to the speed of the power plant adapted to move the control valves so as to open the escape passage from the primary fuel pump when the speed of the power plant falls below the preselected governed speed and to simultaneously close the escape passage from the emergency fuel pump so as to bring the emergency system into action, immediately the speed of the power plant falls below scheduled speed.

2. A device as set forth in claim 1 in which the third governor includes a rotating element, a cylindrical radial chamber therein, a housing enclosing said element, a piston in said radial chamber, a first valve moved by said piston and controlling the pressure on the inner face of said piston, a first axial passage in said rotating element, a port in said passage controlled by said first servovalve, a source of fluid under pressure in said housing acting on the outer face of said piston, a source of fluid at a lower pressure connected to said first axial passage and, when the 75 port controlled by said first servovalve is opened

in response to centrifugal force, admitting this lower pressure fluid to the cylindrical radial chamber to act on the inner face of said piston to maintain said piston in equilibrium, a second axial passage in said rotating element connected to said chamber adjacent to the inner face of said piston, a second chamber, a first moving wall therein dividing said second chamber into two, a passage from one side of said moving wall to the high pressure normally existing in the housing, a passage from the other side being connected to the second radial passage, a second servovalve connected to the first moving wall, a third chamber associated with the control valves, a second moving wall therein connected to said two control valves, yieldable means for moving said control valves and said second moving wall into their emergency positions, a passage from a source of low pressure fluid to said third chamber, said second servovalve being located in said passage, means for admitting high pressure fluid to said third chamber to move said second moving wall and the control valves connected thereto to their normal positions in which the escape from the primary fuel pump is closed, yieldable means engaging with the first moving wall, manually operated linkage for simultaneously changing said yieldable means controlling said second servovalve and the primary and emergency governors.

3. A device as set forth in claim 1 in which there are speed responsive means for rendering said control valves inoperative from the time the power plant is first started until it reaches a preselected low speed so that the system remains in its normal position during the initial stages of the starting operation.

4. A device as set forth in claim 1 in which there are speed responsive means for rendering said control valves operative whenever the power plant operates above a preselected speed so as to bring in the emergency fuel pump and governor whenever excessive speeds are permitted by said primary governor.

5. A device as set forth in claim 1 in which there is an acceleration responsive device which is connected to the speed responsive device and an acceleration responsive valve which is operatively connected to the acceleration responsive device and to the speed responsive device to render the latter inoperative, during acceleration, to bring in the emergency system before a steady speed has been attained.

6. A fuel control system for a power plant of the type in which fuel flow determines speed and in which there is a primary fuel pump and a manually controlled primary fuel governor connected thereto driven by said power plant limiting fuel flow, an emergency fuel pump, a manually controlled emergency fuel governor connected thereto driven by said power plant limiting fuel flow, an escape passage between each pump and each governor, interconnected control valves located in said escape passages for disconnecting fuel flow from the primary governor to the power plant, and for connecting the fuel flow from the emergency governor to the power plant when moved from their normal position to their emergency position, a speed sensing device also driven by said power plant and operatively con-

nected to said valves, said speed sensing device only becoming operative to move said control valves into their emergency position when the speed of the power plant fails to equal that corresponding to that selected by the manual control of said primary fuel governor, a manual control for the speed sensing device, linkage connecting said control to the manual controls of the primary and of the emergency governors so that all three speed responsive devices are simultaneously and manually adjusted.

7. In combination a rotating power plant of the type in which fuel flow determines speed and which is adapted to rotate below one critical speed and above another critical speed, a fuel control which comprises a normal and an alternative fuel supply means for supplying fuel to said power plant, two governing means, both acting in response to the speed of said power plant, one to prevent the speed exceeding the maximum critical speed by restricting the fuel flow, the other to prevent the speed falling below the minimum critical speed by switching from the normal to the alternative and from the alternative to the normal fuel supply, a third speed governing means for the alternative fuel supply to limit the speed by limiting the fuel supply.

8. In combination a rotating power plant of the type in which fuel flow determines speed, a fuel control which comprises two fuel flow systems for supplying fluid fuel to said plant and means acting in response to the speed of said rotating power plant to cut off the one fuel supply system to the power plant as the speed decreases below the predetermined value and to automatically cut in the other fuel supply system to maintain the speed slightly above the predetermined value, two speed responsive governors one acting on each of said two fuel supply systems three manually controlled means, one for selecting the said predetermined limiting value of the speed and two for selecting the speed at which each of the two governors responds to speed, linkage connecting the three means together so that they can be varied simultaneously.

9. In combination a rotating power plant of the type in which the fuel flow determines speed and adapted to rotate below one critical speed and above another critical speed, a fuel control which comprises two alternative fuel supply means, three governing means acting in response to the speed of said power plant, one to prevent the speed falling below the minimum critical speed by switching from one alternative fuel supply means to the other, the other two governing means acting one in each fuel supply means to prevent the speed of the power plant exceeding the maximum critical speed by restricting the flow of fuel to the power plant.
